UNITED STATES PATENT OFFICE.

PAUL SCHMALJOHANN, OF KIEL, GERMANY.

TWO-STROKE CYCLE INTERNAL-COMBUSTION ENGINE OF THE DIESEL TYPE.

Application filed April 15, 1924, Serial No. 706,657.

My invention relates to improvements in two-stroke cycle internal combustion engines of the Diesel type, and more particularly in engines of the type comprising stationary cylinders and reciprocating pistons acting on a rotary member or fly wheel mounted on the driven shaft and formed with cam ways controlling the cycle performed in the cylinders. In order to reduce the size and the weight of engines of this type the cam ways are so constructed that for each rotation of the fly wheel a plurality of cycles are performed in each of the cylinders. However, thereby the time for the individual cycles is unduly shortened. This is not objectionable as far as compression and expansion are concerned, but the regular combustion of the fuel requires a certain time and it must be completed as far as possible at the beginning of the expansion, because otherwise the efficiency of the engine is interfered with by retarded combustion. The object of the improvements is to provide an engine of the class referred to in which a plurality of cycles are performed for each rotation of the fly wheel, and in which the time allowed for the combustion is sufficient to insure complete combustion, and with this object in view my invention consists in constructing the portions of the cam ways corresponding to the combustion strokes so that the length of the portions results in an increased time of combustion, and that during this period of time the pistons move through paths corresponding in the diagram to the line of equal pressure. In my improved engine it can not be entirely avoided that the combustion of a part of the fuel is delayed and that the delayed combustion is continued in a large part of the expansion portion of the cycle if the period of time of the expansion is short. For this reason the cam ways are made so that the expansion period also is lengthened, while the time of the compression is reduced, which reduction, however, is immaterial. By thus constructing the cam ways the time of the complete two-stroke cycle remains the same, and by extending the period of time of the expansion the delayed combustion takes place during a short part of the said expansion period so that the loss caused by delayed combustion is reduced to a minimum.

For the purpose of explaining the invention an example embodying the same has

been shown in the accompanying drawing, in which,

Fig. 1, is a sectional elevation of the engine, and

Figs. 2 and 3, are diagrammatical views showing the form of the cam way.

In the example shown in the drawing the engine comprises a stationary cylinder 1 having two working pistons 2 and 3 reciprocating therein in opposite directions. The pistons are rigidly connected by rods 4 with cross-heads 5 guided in radial guide ways 6 and carrying rollers 7 engaging a cam way. As shown the cam way consists of six sections $b-c-b'$ each controlling a complete two-stroke cycle. The cam way is formed on the inner face of a fly wheel or disk 8 secured to the driven shaft.

The piston 2 controls the exhaust ports 9 and the piston 3 the ports 10 for the admission of scavenging air. The fuel is fed through apertures 11 of the cylinder 1. During the explosion stroke the pistons 2 and 3 and the rollers 7 thereof are forced against the portions $c-b$ of the cam ways, so that the fly wheel 8 is driven in the direction indicated by the arrow x shown in Fig. 1.

In Fig. 2 I have shown a section $b-b'$ of the guide way corresponding to a complete two-stroke cycle, as developed on a straight line, together with the indicator diagram drawn in the proper relation thereto. The section $b-c$ corresponds to the compression line $f-g$ of the indicator diagram, the section $c-d$ to the line $g-h$ of constant pressure combustion, and the line $d-b'$ to the line $h-f$ of the expansion.

The lengths $b-c$ and $c-b'$ when measured by arcs are represented by the lengths l and m respectively which are alike, and which correspond to certain periods of time.

The dotted line $c-e-b'$ shows the form of the cam way of engines with normal crank mechanism as constructed hitherto, the curve $c-e-b'$ being exactly symmetrical to $b-c$. In engines of this type the line of equal pressure represented in the diagram by the line $g-h$ corresponding to a definite piston stroke is passed by the piston within a period of time corresponding to the length i . But when the guide way is shaped according to my present invention, as indicated, by the line $c-d-b'$ the piston passes through the same length $g-h$ of its stroke during a

longer period of time corresponding to the line k , so that there is sufficient time for the combustion even in case of a high number of revolutions of the engine. In my present 5 invention, the section $c-d-b'$ is unsymmetrical with respect to the section $b-c$.

In the diagram shown in Fig. 3 the point c has been shifted to the left for shortening the length n relatively to what has been 10 shown in Fig. 2, and the length o has been increased accordingly as compared with m . The length k has not been changed, so that the expansion is extended in a degree corresponding to the difference of the lengths k 15 and o . Therefore, delayed combustion takes place only on a comparatively small part of the expansion stroke $d-b'$.

I claim:

1. In a two-stroke cycle internal combustion engine, the combination, with a cylinder, and a piston, of a cam way engaged by 20 said piston for controlling the movement thereof, that portion of the curve of the cam way which controls the combustion and 25 expansion being unsymmetrical with respect to the remaining portion of the cam curve in such a way as to increase the time of the combustion without changing the length of the stroke of the piston.

2. In a two-stroke cycle internal combustion engine, the combination, with a cylinder, and a piston, of a cam way engaged by 30 said piston for controlling the movement thereof, that portion of the curve of the cam way 35 which controls the combustion and compression being unsymmetrical with respect to the remaining portion of the cam curve in such a way as to accelerate the movement of the piston during the compression stroke 40 and to begin the combustion stroke accordingly.

3. In a two-stroke cycle internal combustion engine, the combination, with a cylinder,

and a piston, of a cam way engaged by said piston for controlling the movement thereof, 45 that portion of the curve of the cam way which controls the combustion, expansion and compression being modified from the curve corresponding to the operation by means of a crank mechanism in such a way 50 as to accelerate the movement of the piston during the compression stroke and begin the combustion stroke accordingly and retard the movement of the piston during the combustion and expansion stroke. 55

4. In a two-stroke cycle internal combustion engine, the combination, with a stationary cylinder, and a piston reciprocating therein, of a rotary annular driven member formed with a cam way engaged by 60 said piston for controlling the movement thereof and for being driven thereby, that portion of the curve of the cam way which controls the combustion and expansion being modified from the curve corresponding to the operation by means of a crank mechanism in such a way as to increase 65 the time of the combustion without changing the length of the stroke of the piston. 70

5. In a two-stroke cycle internal combustion engine, the combination, with a stationary cylinder, and a piston reciprocating therein, of a rotary annular driven member formed with a cam way engaged by 75 said piston for controlling the movement thereof and for being driven thereby, that portion of the curve of the cam way which controls the combustion and compression being modified from the curve corresponding to the operation by means of a crank mechanism 80 in such a way as to accelerate the movement of the piston during the compression stroke and begin the combustion stroke accordingly. 85

In testimony whereof I hereunto affix my signature.

PAUL SCHMALJOHANN.
